METHOD OF CONCEALING DEFECTS IN A SURFACE

Alfred E. Kowall, Westchester, Ill., assignor of one-half to Edward A. Kirwin, Wilmington, Del.

No Drawing. Application November 27, 1951,
Serial No. 258,531

3 Claims. (Cl. 117—2)

1

This invention relates to an improved patching composition and to a method of making and using such composition and has for an object to provide an improved composition to be used as a patching material for filling minor defects such as scratches, cracks and nail holes in a surface that is to be painted with a flat finish, water or oil paint, which improved composition may be applied to the defect in a wet plastic condition and then may be painted over immediately without first having to wait until the patch is dry, and the patch will be completely concealed and become a part thereof beneath the covering paint thereover.

A further object of this invention is to provide a patching material that is self sealing and produces a smooth surface. The patch does not require sanding when it is knifed in clean or smoothed over with what painters call a "dry" brush, that is a brush that has been dipped in paint and then had most of the paint worked out of it. The patch may be painted over while still wet to produce a smooth finish surface wherein the defect or patch will not be visible or burn through or bleed through the covering paint after the covering paint has dried.

Still a further object of this invention is to provide an ingredient for a patching composition which is very inexpensive to manufacture and transport in a compact powdered form to wherever it is to be put in use and which may be easily and readily mixed by the painter just before it is to be used on the job.

A further object of this invention is to provide a patching composition that will not discolor or burn through the covering paint thereover even though the covering paint is placed over the patch while the patch is still wet irrespective of whatever color the paint is, and is thus an improvement over present known compositions for this purpose which usually must dry completely and then be given a coating of sealer that must also thoroughly dry before it can be painted over. This invention eliminates this loss of time by putting the patching composition over the defect and covering it with a finishing paint, and with this invention, the patch will be invisible after the finishing or covering paint has dried.

Still a further object of this invention is to provide an improved patching composition which is used in the form of a thick paste or putty like consistency which may be painted over immediately while it is still wet, and wherein the binder for the paste or putty like composition consists of whatever liquid finish or flat finish

2

paint that is being used to paint the surface at the time.

Yet a further object of this invention is to provide a process for concealing minor defects in a wall being painted by knifing in or filling the defect with a thick paste or putty like composition consisting of a composition of common mica, neutral or light colored, and ground to a suitable mesh of between 160-180 or better mixed with a binder consisting of the particular paint or liquid material being used to paint or finish the wall with.

The essential feature of this invention is that it consists of a material in a dry powdered form which may be stored indefinitely and transported easily, and which is mixed on the job as needed and then may be applied to the surface defect to provide a smooth finish surface which may be painted over immediately while it is still wet, and then when the covering paint has dried, neither the patch nor the outlines of the defect will be visible through the dried paint either then or a later time, and will be at patch that requires no sanding if knifed in clean or brushed over lightly as in the manner mentioned above.

In putting this invention into use, it will be understood that it will always mix to its desired consistency by blending it with the same liquid material or paint that will be used to cover or paint the surface after the patching has been completed. The liquid material should never be thinner than the liquid material that will be put on the surface, preferably straight from its container whenever possible for best results. The powdered material consists of common mica, a mineral, which has been ground to a fineness of between 160-180 or better. In order that the powdered mica may be usable with any color paint or finish, it is preferably always a neutral or light colored mica so that it can be mixed with both light or dark colors.

Another feature of this composition that has the advantage over present day compositions used for this purpose is when used on jobs where a large number of rooms are usually painted using the same color. An amount sufficient to last several days can be made without fear of it going to waste. It may have a tendency to thicken in body the next day after it is mixed which is due to evaporation of the thinner that is in the binder it was mixed with. However, it can be rejuvenated or brought back by adding a little of the same liquid material that was used for its binder originally and working it under a broad knife or a putty knife or putting it in a

container such as a tin can and stirring it up with a stick.

The mica for this purpose will be ground to a fine powder of at least about 160-180 mesh and then suitably packaged for storage and transportation with instructions that in order to use the same as a patching composition, it should be mixed with the particular paint or liquid material that is being used to paint or finish the wall with. Then, the painter at the job following the instructions will add a sufficient quantity of whatever flat finish paint or liquid finish he is covering the wall with to a suitable quantity of the powdered mica to make a thick paste or putty-like composition or to the consistency most suitable for his purpose, then he will fill in the minor cracks or defects in the wall with this composition, knifing it in as customary and smoothing it out in the manner described above for a patch that will not require sanding, and then without having to wait for it to dry or to cover it with a sealer after it is dry, he merely continues with his normal painting operation covering over the wet patch and will have a perfect finish when he is through. Cracks and holes over one inch or major defects in the wall or surface to be covered must first be filled with a quick-drying patching material such as plaster of Paris, and then have its surface covered with this patching composition as soon as it has set, even though not fully dry, and then it is treated as above and may be painted immediately.

A great advantage of this patching composition is that all small defects will be covered to a smooth finish so that the finished painted surface will be smooth and any defect thereunder will no longer be visible through the painted surface and the covering paint will never be discolored by having the patch become visible or burn or bleed through the paint.

The same class of micas that are used in this invention as thus far described are also very desirable in producing an improved putty composition, wherein the mica is used instead of whiting as customary, which putty composition is useful in all the uses of ordinary putty, including the glazing of glass in windows and the filling in of nail-holes before painting, even though not otherwise generally useful for covering defects before painting. Such improved putty composition, wherein the common micas of the class useful in the patching compositions are substituted for whiting, is extremely smooth and silk like in texture, and much easier to work than ordinary putty to which whiting is often added to absorb excess oil.

While the preferred composition of this invention has been set forth and described, it will

be understood that this invention is not restricted except as may be required within the scope of what is hereinafter claimed.

Having thus set forth and disclosed the nature 5 of this invention, what is claimed is:

1. The process of concealing minor defects in a surface being covered with a flat finish of oil or water base paint consisting of first covering the defect with a thick paste consisting of common ground mica mixed with a sufficient quantity of the particular covering paint, and thereafter applying the paint while the paste is still wet.
2. The method of concealing minor defects in a surface being covered with a flat finish or oil or water base paint consisting of using a sufficient quantity of the same covering paint as a carrier and mixing with common mica, which has been ground to a fineness of 160-180 or better, to a thick paste, then knifing the thick paste into the minor defect, and thereafter painting over the paste in the defect while the paste is still wet.
3. The method of concealing minor defects in a surface being covered with a flat finish or oil or water base paint consisting of using a sufficient quantity of the same covering paint as a carrier and mixing it with common light or neutral colored mica, which has been ground to a fineness of 160-180 or better, to a thick paste, then knifing the thick paste into the minor defect, and thereafter painting over the paste in the defect while the paste is still wet.

ALFRED E. KOWALL.
